US00D780534S

(12) **United States Design Patent** (10) **Patent No.:** **US D780,534 S**
(45) **Date of Patent:** **** Mar. 7, 2017**

(54) **CONTAINER FOR SANDWICH INGREDIENT**

(71) Applicant: **Jesse Oliver**, Texas City, TX (US)

(72) Inventor: **Jesse Oliver**, Texas City, TX (US)

(**) Term: **15 Years**

(21) Appl. No.: **29/545,957**

(22) Filed: **Nov. 17, 2015**

(51) **LOC (10) Cl.** **07-01**

(52) **U.S. Cl.**

USPC **D7/629**

CLAIM

The ornamental design for a container for sandwich ingredient, as shown and described.

DESCRIPTION

FIG. 1 is a top perspective view of a container for sandwich ingredient showing my new design;

FIG. 2 is a bottom perspective view thereof;

FIG. 3 is a front elevational view thereof, the rear view being a mirror image;

FIG. 4 is a left side elevational view thereof;

FIG. 5 is a right side elevational view thereof;

FIG. 6 is a top plan view thereof;

FIG. 7 is a bottom plan view thereof;

FIG. 8 is an exploded top perspective view thereof; and,

FIG. 9 is an exploded bottom perspective view thereof.

1 Claim, 9 Drawing Sheets
